UNITED STATES PATENT OFFICE.

FREDERICK S. ANABLE, OF BOSTON, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,147,290.

Specification of Letters Patent. Patented July 20, 1915.

Application filed August 19, 1908. Serial No. 449,320.

To all whom it may concern:

Be it known that I, FREDERICK S. ANABLE, a citizen of the United States, residing at Boston, in the county of Suffolk and State 5 of Massachusetts, have invented an Improvement in Strip-Serving Devices, of which the following description, in connection with the accompanying drawings, is a specification, like letters on the drawings 10 representing like parts.

This invention relates to devices or apparatus for supplying strips of paper or the like, employed for wrapping or binding packages or for use as labels of any desired 15 length, and has particular reference to that type of apparatus employing a support for a coil of paper strip previously gummed and then dried, and having provisions for moistening the gum upon the strip as the latter 20 is drawn from its coil. It is apparent that an ungummed strip of paper or the like may be employed, in which case the moistening device for the strip suitably positioned with respect thereto would contain an adhesive 25 instead of water.

In order that the principles of the invention may be clearly understood, I have disclosed certain types or embodiments thereof in the accompanying drawings, where- 30 in—

Figure 1 is a side elevation, partially in section, of a strip serving device embodying one form of my invention; Fig. 2 is a view in rear elevation with parts broken away of 35 the moistener and severing device and parts relating thereto; Fig. 3 is a side elevation of a strip serving device embodying another form of my invention; Fig. 4 is a plan view of a portion of the device shown in Fig. 3; 40 Fig. 5 is a side elevation of another form of strip serving apparatus embodying my invention; Fig. 6 is a portion of the view of the device shown in Fig. 5; Fig. 7 is a side elevation of still another form of my invention; Fig. 8 is a plan view of a portion of the device shown in Fig. 7.

I contemplate the provision of means whereby the strip may be severed by strip pressure. This may be accomplished in 50 many ways, as, for example, by strip pressure upon the moistener or upon a part other than the moistener. It is apparent that strip pressure may be employed to sever the strip either in advance of or in the rear of 55 the moistening point. In the several forms

of my invention herein chosen for illustration, the strip is represented as severed by strip pressure in the rear of the moistening point.

Referring first to the form of my invention disclosed in Figs. 1 and 2, the strip support is represented at 1, it being of any suitable construction and being preferably a case wherein a roll of paper may be suitably supported and tensioned. Herein it is 60 represented as mounted upon a base 2. Suitably secured to the base is a reservoir 3 having mounted therein for movement toward and from the service path of the strip a moistener 4 of any suitable construction. 65 Herein the moistener is represented as a wicking having ends depending into the tank or reservoir. The moistener is supported by spring 5 which normally projects the same toward the service path of the strip, but upon the application of strip pressure to the moistener, the spring 5 yields and the moistener is moved downwardly from the normal service path of the strip. Any 70 suitable means may be employed to sever the strip by strip pressure induced movement of the moistener. Herein I have represented the severing blade 6 guided in suitable ways 75 extending from the tank or reservoir 3. The blade 6 may be of any suitable construc- 80 tion and either serrated, as shown in Fig. 2, or it may be formed as an inverted V or W, so that the point or points thereof may readily penetrate the strip to sever the same. While the blade may be operated in any 85 suitable manner upon movement of the moistener, herein I have represented levers 8 pivoted at 9 upon the reservoir and jointed at 10 to the arm 11 of the blade and at 12 to arms 13 suitably pivoted to the moistener 90 at 14. The walls of the moistener are suitably slotted to permit the described movement of the moistener. Preferably the strip should be tensioned so that it may be more readily severed when the blade is projected. 95 Herein, for the purpose, I have represented rolls 15 and 16 suitably supported from the tank or reservoir, the upper roll 16 being spring pressed by springs 17 toward the lower roll. Preferably and as shown, the 100 spring tension is adjustable and the construction of parts is such that the rolls may be readily separated sufficiently to permit the insertion of the free end of the strip therebetween.

110

Any suitable means other than the moistener may be utilized to receive strip pressure and transmit the same to the severing blade. In Figs. 3 and 4, I have represented 5 a bar 18 mounted in a casing 19 and suitably projected toward the service path of the strip by a spring 20. Said bar is operatively connected in any suitable manner with the severing blade 21, as by means of 10 levers 22 represented as pivoted at 23 upon the reservoir.

In Figs. 1 to 4 inclusive, I have represented the blade as movable. It is apparent, however, that the same may be fixed and 15 that the strip may be moved by strip pressure into severing relation thereto. Such a construction is represented in Figs. 5 to 8 inclusive.

In Figs. 5 and 6 is represented a fixed 20 blade, into severing relation with which the strip is moved by strip pressure applied to the moistener, while in Figs. 7 and 8 the strip is similarly moved by strip pressure applied to a part other than the moistener.

25 In said Figs. 5 and 6, the fixed blade 24 is suitably supported upon members 25 extending from the tank or reservoir. The moistener 26 is preferably supported by a spring 27 in the manner illustrated in Figs.

30 1 and 2. Vertically beneath the blade 24 is a suitably guided plunger 28 preferably slotted at its upper end and pivotally connected at 29 to levers 30 pivoted at 31 upon the tank or reservoir and jointed at 32 to

35 arms 33 pivotally connected at 34 to the moistener. It will be apparent, when the moistener is moved downwardly by strip pressure, that the plunger will be projected to carry the strip into severing relation with 40 the fixed blade 24.

In the construction shown in Figs. 7 and 8, the bar 35 is adapted to be depressed against the springs 36 by strip pressure, and thereby through the levers 37 to project the 45 plunger 38 carrying with it the strip against the fixed blade 39 to sever the same.

The severing blade may be positioned in any suitable relation to the moistening point.

It is apparent that in the various forms of 50 the invention spring means may be employed to support the member to which spring pressure is to be applied.

Having thus described types or embodiments of my invention, I desire it to be understood that although specific terms are employed, they are used in a generic and descriptive sense and not for purposes of limitation, the scope of the invention being set forth in the following claims:

60 1. A strip serving device comprising a strip support, a moistening device, strip severing means positioned transversely of the strip, and means for operating said severing means through the instrumentality of said 65 moistening device.

2. A strip serving device comprising a strip support, a yieldingly mounted moistener, strip severing means, and connections between the severing means and the moistener to project the severing means by yielding movement of said moistener, thereby to sever the strip. 70

3. A strip serving device comprising a strip support, a spring supported moistener, a movable severing blade arranged transversely of the strip, and connections intermediate the blade and moistener to operate the former. 75

4. A strip serving device comprising a strip support, a moistener, and movable strip 80 severing means positioned transversely of the strip and movable by strip pressure applied to the moistener to sever the strip. 85

5. A strip serving device comprising a strip support, a moistener, movable strip 90 severing means positioned transversely of the strip, said strip severing means being moved by strip moistening deflection into engagement with the strip, thereby positively to sever the same. 95

6. A strip serving device comprising a strip support, a strip moistening device in front thereof and against which the strip is adapted to be bodily deflected for moistening, movable strip severing means, and 95 means actuated by said deflecting movement of the strip against the moistener, to move the severing means into engagement with and thereby positively to sever the strip.

7. A strip serving device comprising a 100 strip support, a strip moistening device positioned in the service path thereof and against which the strip is adapted to be bodily deflected for moistening, a movably mounted strip severing blade, and lever connections between the moistener and the blade, thereby to sever the strip upon moistener movement. 105

8. A strip serving device comprising a strip support, a strip moistening device in 110 the service path thereof and against which the strip is adapted to be bodily deflected for moistening, strip severing means positioned transversely of but normally removed from contact with the strip, and actuating connections between the moistener and said means to project the latter into severing relation with the strip. 115

9. A strip serving device comprising a strip support, movable means positioned in 120 the service path of the strip and against which the strip is adapted to be bodily deflected in the strip moistening movement, strip severing means arranged transversely of the strip, but normally spaced therefrom, 125 and actuating connections between said movable means and strip severing means to cause said strip severance.

10. A strip serving device comprising a strip support, a spring supported strip mois- 130

tening device arranged in the service path of the strip, a severing blade between the strip support and the moistener and movably mounted to be projected into severing relation to the strip, and actuating connections between said moistener and said blade, thereby to project the blade upon yielding movement of the moistener.

11. A strip serving device comprising a strip support, a bodily movable moistening device, strip severing means and connections for causing operation of said strip severing means by bodily movement of said moistening device.

15 12. A strip serving device comprising a strip support, a movable moistening device, movable strip severing means, and connect-

ing means between said moistening device and said severing means to cause the movement of the moistening device to effect strip severing movement of the severing means.

13. A strip serving device comprising a strip support, a moistener and movable strip severing means movable by strip pressure manually applied to the free end of the strip in a direction normal to the service path of the strip, thereby to sever the strip.

In testimony whereof, I have signed my name to this specification, in the presence of two subscribing witnesses.

FREDERICK S. ANABLE.
